UNITED STATES PATENT OFFICE.

CHARLES W. CUMMINGS, OF ATOLIA, CALIFORNIA, ASSIGNOR OF ONE-HALF TO CARL N. DUNNELL, OF ATOLIA, CALIFORNIA.

CARBURETER.

1,129,794.

Specification of Letters Patent. Patented Feb. 23, 1915.

Application filed February 8, 1913. Serial No. 747,085.

To all whom it may concern:

Be it known that I, CHARLES W. CUMMINGS, a citizen of the United States, residing at Atolia, county of San Bernardino, 5 State of California, have invented a new and useful Improvement in Carbureters, of which the following is a specification.

This invention relates to carbureters and particularly to carbureters for vaporizing 10 fuels of a heavy grade, or fuels which do not vaporize readily under ordinary temperature, and the principal object is to provide the carbureter supply with a plurality of passages which are adapted to be heated by 15 contacting with the heated fluids exhausting or used by the motor.

It is also an object to provide a carbureter of which both the intake and exit from the mixing chamber are extensions of passages 20 adapted to be heated and surrounded by a casing adapted to confine the heating medium.

It is a further object to provide a carbureter in which the auxiliary air intake also 25 controls the entrance thereto of a vaporizing fluid, not commonly used as a fuel.

In the drawings accompanying this specification, Figure 1 is a longitudinal vertical section through the two passages carried 30 through the heating chamber and the attached parts. Fig. 2 is an end view of the carbureter, viewed from the side having the auxiliary fluid inlet. Fig. 3 is a plan view of the carbureter, the intake manifold to 35 which it is secured being shown in section. Fig. 4 is an enlarged detail section of the auxiliary fluid inlet with its controlling valve.

In the drawings, numerals are used to 40 designate the same portions, 7 designating the hollow body through which are carried the plurality of longitudinal disposed passages formed by suitable walls cast integrally with the body 7, which is of general 45 rectangular form, the upper face 8 of which is adapted to be secured to the intake manifold 9 of an explosive or internal combustion engine by suitable bolts 10, this manifold registering with the upper end of the 50 passage 11, which is carried to the lower wall or bottom of the body 7, and provided with a flange 12, to which is secured the flange of the mixing chamber 14, of a standard type of casting, to which is secured the 55 float chamber 15, provided with a fuel inlet

16 and the air inlet 17 directly connected to the mixing chamber. The upper or open portion of the air inlet 17 is connected to the plug 18 secured in the lower portion of the extension 20. An air supply passage 19 is 60 formed also integrally with body 7, having a dependent section which connects with an extension from the mixing chamber 14 at the point 21, this portion being shown as integral with the common type of casting 65 previously mentioned, the lower opening found connected therewith being closed by the screw fitted plug 18.

The upper end of the passage 19 opens in the side wall oppositely disposed to that 70 nearest the passage 11 and preferably opens outward forming a lateral extension 22, provided with threaded apertures in the upper and lower faces of this extension, and a lateral direct inlet 41, the upper opening being 75 closed by a suitable plug 23, against which the spring 24 on the valve rests.

The lower orifice is preferably closed by the annular ring or bell 25, the upper edge of which is provided with a valve seat 26 on 80 which rests the valve 27, the bevel face being shown as forming the valve seat. This auxiliary air valve is provided with a valve stem 28, which is suitably mounted so that the valve is lifted concentrically off of its 85 seat to allow even distribution of the air when the suction on the carbureter is sufficient to lift this valve against the tension of the spring.

Entering into the casting and having its 90 opening on the valve seat 26 is the bore 29; the outer end of the bore being of greater diameter, and preferably threaded to receive the supply pipe 30 adapted to carry water under pressure from a suitable source 95 of supply.

Access to the chamber 31 formed by the surrounding walls of the body 7 and the similar walls forming the various passages described, is had through an inlet opening 100 32 which is preferably of such size as to have the exhaust pipe 33 from the motor connected therewith and the exit therefrom being in the oppositely disposed end-wall and preferably on a lower level, is the opening 105 34, to which the extension of the exhaust pipe 35 is secured in any well-known manner.

In the operation of this carbureter, in 110 starting, a lighter fuel than that for which

it is primarily adapted to be used is introduced, as gasoline, through the fuel intake 16 from a source of gasoline supply, and the engine started on this fuel, it being customary to run the engine slow during this preliminary warming-up until the walls of the passages are sufficiently heated by the exhaust passing through or the hot water used as it makes its exit from the hot cylinders, when, by the use of a three-way valve placed in fuel line on the dash-board, not shown, the fuel is shifted to a heavier gravity, which requires a greater heat to vaporize and which heat is absorbed by the mixture of the latter with heated air brought in through the air intakes and also heated in its passage from the mixing chamber to the engine intake. When the speed becomes such that more air is desired and the throttling 20 so regulated that the auxiliary air valve 27 is lifted to admit the auxiliary air, water heated in its flow through the heated jackets of the engine or from any other source, is admitted at the same time by the uncovering 25 of the valve seat, and is distributed and vaporized and carried into the cylinders to increase the efficiency of the expansion of the explosive charge.

What I claim is:

30 1. A carbureter comprising a hollow body having an inlet and outlet, adapted to be connected to a source of heated fluid, and having a plurality of walled passages there-through, one of said passages having a plurality of inlets, a valve to control one of said

air inlets in said passage, a fuel mixing chamber connected to the other end of said passage, and a source of fuel supply having an inlet into said mixing chamber, said mixing chamber being connected to another of 40 said passages in said body.

2. A carbureter, comprising a hollow body having a plurality of walled passages there-through, forming inlet and outlet passages, a pressure controlled valve adapted to admit air to one of said passages, a valve seat for said valve, means to introduce an auxiliary fluid to said valve seat, a mixing chamber, and a fuel inlet, the exit of the mixture formed being controlled through the other 45 50 of said passages.

3. A carbureter, comprising a hollow body having an inlet and outlet, adapted to be connected to a source of heated fluid, and having a plurality of walled passages there-through, one of said passages having an inlet, a valve to control said inlet, a fuel mixing chamber connected to the other end of said passage, and a source of fuel supply having an inlet into said mixing chamber, 55 60 said mixing chamber being connected to another of said passages in said body.

In witness that I claim the foregoing I have hereunto subscribed my name this 22nd day of January, 1913.

CHAS. W. CUMMINGS.
